UNITED STATES PATENT OFFICE.

BRUNO H. HEYNE, OF RICHMOND, CALIFORNIA.

STEAM BOILER.

Application filed August 3, 1922. Serial No. 579,396.

The present invention relates to a steam boiler of the water tube type and which is particularly adapted for automotive purposes.

5 An object of the invention is to provide a simply constructed, relatively small, compact and highly efficient steam generator of the character described, which in comparison to the types of steam generators 10 such as now used for automotive purposes is superior thereto, in that, it is more economical to operate, is not subject to being rendered inoperative due to burning out of tubes or to failure of a part or parts 15 of the boiler to operate, is self cleansing, operates under a minimum amount of expansion and contraction, is expeditious in its production of steam, and has a comparatively small area, thus providing an ap- 20 preciable safety factor.

Another object of the invention is to provide a steam generator of the character described which comprises essentially a plurality of independent generating sections, a 25 drying section for each generator with a single economizing section, all being compact and of an arrangement such that upon burning out of one of said sections, said inoperative section may be shut off from 30 operative association with the remaining sections and the generator may be operated without material loss of efficiency.

The invention possesses other advantages and features some of which, with the foregoing will be set forth at length in the following description where I shall outline in full that form of the invention which I have selected for illustration in the drawings accompanying and forming a part of the 40 present specification. In said drawings I have shown one form of the construction of my invention, but it is to be understood that I do not limit myself to such form since the invention as expressed in the claims may be 45 embodied in a plurality of forms.

Referring to the drawings:

Fig. 1 represents a vertical sectional view of the boiler of my invention showing most of the boiler sections in elevation and cer- 50 tain thereof in section.

Fig. 2 represents a front elevation of the boiler with a part of the front wall of the casing removed so as to show the sections of the boiler in front elevation.

Fig. 3 represents a rear elevation of the 55 boiler with the rear wall broken away and certain parts shown in section.

The embodiment of the invention illustrated in the accompanying drawings comprises a casing generally designated 1, which is mounted so that it may be readily applied for automotive use, said casing being substantially rectilinear in outline and completely housing the generator of the invention. The generator comprises a plurality, for example, six or more independent generator sections generally designated 2, each of which sections comprises a circulatory system of water tubes, preferably arranged in a vertical series 3, an upwardly 60 and outwardly inclined series 4, and a series 5 which inclines upwardly and rearwardly from the upper ends of the series 4. The water tubes of the series 3 are welded to headers 6 and 7 carried on opposed ends 65 of elbows 8 and 9. The series 4 of water tubes is welded to headers 10 and 11 carried on the other end of the elbow 8 and one end of an elbow 11'. The series 5 of water tubes is welded to headers 12 and 13, carried 70 respectively on the other ends of the elbows 9 and 11'. The plurality of generator sections 2 are arranged so that the elbows 8, 9 and 11' are in contact with one another. Through this arrangement the boiler is 75 made compact and rigid and a slight space 80 is provided between the series of water tubes 85 of the respective generating sections.

Extending along the upwardly and outwardly inclined bottom of the casing 1 is a suitable burner 14, the flames from which are directed upwardly so as to impinge upon the series 4 of the water tubes of each section.

Connected with each generator section is 90 a drying section comprising an upright tube 15 connected with the upper side of the elbows 9 and having at its upper end a safety valve 16. Extending longitudinally from the upright tube 15 are a plurality of drying tubes 17 arranged one above the other with their outer ends in communication with an upright tube 18 corresponding to the tube 15, said tube 18 being connected with a frame element 19 which is in turn connected 95 with the casing 1. From the upper end of the tube 18 a pipe 20 extends and is connected with a primary steam collecting 100 105

drum 21, which latter extends the full length of the casing above the various sections. In the pipe 20 is a suitable valve or stop-cock 22, access to which may be had by removing the flanged cover 23 of the casing 1. From the collecting drum 21 extending between the several generating and the drying sections are super-heater pipes 24 in U form, the upper ends of said pipes being in communication with the drum 21 and similar drum 25 opposite the drum 21. The drums 21 and 25 are connected with one another by suitable bracing members 26 and have connection with the drying sections by braces 27 and 28. The steam having entered the collecting drum 25 will pass through an outlet 29 into the throttle controlled pipe, not shown, to the engine, likewise not shown. Thus, it will be seen that as shown in the drawings, where six generating sections are provided, there will be a drying section for each generator section and two collecting drums, such as the ones 21 and 25, to which drums the drying sections are connected.

Associated with the generating and drying sections is an upright economizer section generally designated 30, which section comprises a plurality of water tubes 31 attached to upper and lower headers 32 and 33, which headers extend for the full length of the casing 1, horizontally and rearwardly of the several generator sections. The tubes 31 extend from points near the lower ends of the elbows 8 to points substantially at the upper ends of the elbows 9 and are close to the upright tubes of the generating section. The upper header 32 has a water intake opening 34 at one end and for feeding water to the respective generator sections, a plurality of feed pipes 35 arranged in substantially U form are connected at their ends with the lower header 33 and lower portions of the elbows 8. The water feed pipes 35 have controlling valves 36 therein, the actuating means of which valves are located outside of the casing 1 so as to be accessible for operation. Thus it will be seen that each of the generating sections is supplied from the economizer section and that the water will fill the tubes of the respective series 3, 4 and 5 of each generating section and likewise seek the same level in the tubes 31 of the economizer section, the normal water level being indicated at the dotted line L. By supplying water to the boiler it will be seen that the water will simultaneously fill the tubes of the generator sections and the economizer section.

A pipe 37 is connected with the upper end of the tube 15 of each drying section and is connected at its other end with the upper header 32 there being a suitable valve 38 in said pipe 37. By means of the pipe 37 the steam generated will be conducted into the

header 32. The steam also assists in the heating of the water in said tubes 31.

As a means for providing for the collection of sediment and foreign matter, each of the generator sections is provided with sediment traps 40 extending downwardly from the lower wall of the casing 1. A suitable drain pipe 41 is provided in each of the traps 40. A blow-off pipe 42 is extended from the lower header 33 out through the rear wall of the casing 1 and is valved as at 43 at its outer ends. The casing 1 at the rear side of its upper end is provided with an up-take draft flue 44 which may be arranged other than shown as is customary in steam generators.

As a means for bracing the structure, any number of frame elements may be incorporated, for example, as shown at 45 and 46 and also as at 19, with the casing 1. The drying sections are made secure by stay bolts 47 which extend through the tubes 17 and are fastened at their ends to the tubes 15 and 18.

Assuming that the tubes of the sections 2 and the tubes of the economizer section 30 are filled with water up to the level shown at L, when the burner 14 is operated the flames therefrom will extend upwardly around the tubes of the several generating sections. Heat of the burner will also effectively heat the U-shaped super-heater pipes 24 which are extended downwardly between the tubes of the series 5 to a point adjacent the tubes of the series 4. Heat of combustion will heat the drying tubes 17 and likewise the tubes 31 of the economizer section 30 and a maximum utilization of the heat produced is provided for by the arrangement of the tubes of the various sections and parts of the boiler.

Steam generating in the generating sections will rise and pass into the elbows 9 which are uppermost of the said generating sections and will disengage from the water at the water level line L, pass up through the tubes 15 of the respective drying sections and then be directed laterally through the tubes 17 of said drying sections into the upright tubes 18.

The supplying of steam into the economizer section will also assist in the heating of the water in said economizer section. The steam passing from the tubes 17 into the upright tubes 18 will pass into the collecting drum 21. From the drum 21 the steam passes downwardly through the U-shaped super-heating pipes 24 where it is effectively super-heated by being brought back and close to the burner. The super-heated steam passing out through the tubes 24 will collect in the drum 25 and from thence will be supplied to the engine, not shown, through the outlet 29. The water is supplied to the economizer section through the opening 34

by an automatic supply system, which, it is thought need not be described, as such water supply systems are common in the art.

One of the essential features of the invention is that the boiler provides for a free circulation of the water which rises upwardly through the tubes of the series 4, the tubes of the series 5 and then passes downwardly through the tubes of the series 3 back to the lower end of the tubes of the series 4. By this circulation all mineral substance separated by heating the water, as well as the residue from lubricating oils, heavier than water, will be directed downwardly and settle in the residue traps 40. By arrangement of the tubes and elbows, dead eddies and corners which contribute to the collection of residue are eliminated.

Should one of the generating or drying sections become disabled, for example, as when burned out, by cutting off the disabled section, said section is immediately rendered inoperative but without in any way affecting the operativeness of the remaining sections, and the boiler may thus operate with efficiency. In this way it is unnecessary to make repairs if the said section is rendered disabled while under way on the road. The fact that the boiler is sectional and any one or more sections may be cut out without rendering the entire unit inoperative is one of the most essential features of the invention. In the ordinary type of automotive steam generator, the burning out of the tube renders the entire generator unfit for use and requires that repairs be immediately made, whereas with the boiler of my invention, the burning out of a series of tubes or a tube or of more than one section, will not prevent functioning of the generator. It will be noted that the construction is tubular as well as sectional and due to this the danger of explosions is reduced to the minimum as compared to the shell boiler construction. Should a section become so disabled that its removal is necessary, said removal may be effected without disturbing the other sections and a new section easily mounted in place.

I claim:

1. A steam boiler comprising a plurality of independent generator sections, each of which comprises a plurality of annularly related water tubes associated to provide a circulatory system, an economizer section having a water feed intake and comprising a plurality of upright water tubes and head-

ers therefor, feed tubes from one of the headers leading to the lower ends of the respective generator sections, a plurality of drying sections connected with the upper ends of each of the generator sections, means providing for the induction of steam from each of the generator sections into the upper header of the economizer section, means for conducting of steam from the drying sections and a burner arranged so that the flames thereof will directly heat the generator sections and the heat thereof will affect the tubes of the economizer section, and said drying sections.

2. A boiler comprising a plurality of independent generating sections each comprising a plurality of series of water tubes connected with one another at their ends by fittings, an economizer section comprising a plurality of upright water tubes and headers to which said tubes are connected, the upper header having a water intake opening, tubes leading from the lower header to lower portions of the respective generating sections, a plurality of drying sections associated with the generating sections and each comprising upright tubes, one of which is connected to the upper portion of a generating section, drying tubes having their ends connected with the last named upright tubes, a plurality of pipes leading from the drying sections to the upper header of the economizer section, means for taking off steam from the drying section and a burner extending beneath the generating sections, the drying and economizer sections being arranged to be heated by the burner.

3. A boiler comprising a plurality of independent steam generating sections arranged one along side of the other in close relation, an economizer section extending along side of the several generating sections and comprising a plurality of upright water tubes and upper and lower headers to which the tubes are connected, one of the headers having a water intake opening, a plurality of pipes leading from the last named header to the lower portions of the respective generator sections, means for conducting steam from the generator sections to the upper header of the economizing section, a collecting drum into which steam from each of the sections is delivered and means providing for the cutting out of any one of the generator sections without affecting the operation of the remaining generator sections.
